UNITED STATES PATENT OFFICE

2,121,260

LIGHTING CONSTRUCTION

Paul D. Phillips, Elmhurst, Ill., assignor to Benjamin Electric Mfg. Company, Des Plaines, Ill., a corporation of Illinois

Application January 30, 1936, Serial No. 61,445

1 Claim. (Cl. 240—143)

My invention relates to a lighting construction.

In my prior patent, No. 1,834,318, dated December 1, 1931, is shown a construction in which a reflector carrying a lamp socket can be connected and disconnected with respect to a wiring base by means of a bayonet joint connection. In this construction, the connecting and disconnecting movement requires that the wiring base be forced inwardly against a substantial spring pressure to release it from latching engagement. Under some conditions, it is somewhat difficult to effect this inward movement of the wiring base against spring pressure, particularly in the pendant type of fixture in which the hood carrying the wiring base may be supported by a chain. This makes a non-rigid support for the wiring base, making it necessary for anyone disconnecting the fixture to hold the upper element, including the hood and wiring base, with one hand while at the same time holding the reflector carrying the socket with the other hand and pressing it upwardly to compress the wiring base against its spring.

One of the objects of my invention is to provide an improvement in this type of fixture in which a latch member is provided to lock the bayonet joint in connected position, which latch, when released, will enable the parts to be disconnected by simply rotating the reflector carrying its socket with respect to the hood carrying its wiring base.

A further object of my invention is to provide such a latch which may be easily released by the hand holding the hood.

Further objects and advantages of the invention will be apparent from the description and claim.

In the drawing, in which an embodiment of my invention is shown,

Figure 1 is an axial section;

Fig. 2 is a section on the line 2—2 of Figure 1;

Fig. 3 is a side elevation of the hood and latch, parts being broken away;

Fig. 4 is a side view of the neck of the reflector with the bayonet joint member;

Fig. 5 is a side elevational view of the hood with a part broken away to show a bayonet joint lug; and

Fig. 6 is a bottom view of the wiring base.

Referring to the drawing in detail, the lighting construction shown comprises a hood 1 which may be supported in any suitable manner as by a stem or chains, a wiring base 2 in, and carried

by, said hood having contacts 3 and 4 thereon for

engaging corresponding contacts 5 and 6 on the lamp socket 7 and having a bayonet joint connection with the hood, a reflector member having an upper neck portion 8 and having a bayonet joint member 9 for connection with a bayonet joint formation on the hood, the lamp socket 7 mounted on and carried by the reflector having the contacts 5 and 6 for engaging the contacts 3 and 4 on the wiring base, and latching means for holding the reflector against rotation when in connected position with respect to the hood, said latching means comprising a spring-pressed plunger 10 having a laterally extending arm 11 engageable by the hand holding the hood for releasing the plunger.

The bayonet joint connection between the wiring base 2 and hood 1 may be substantially as shown in my Patent No. 1,834,318, the hood being provided with a number of inwardly extending lugs 12 and the insulating wiring base being provided with a plurality of L-shaped recesses 13 in its sides for cooperation with the lugs 12 on the hood. A coil compression spring 14 is provided, acting between the hood and wiring base, to hold the wiring base against rotation when in connected position. When in connected position, the lugs 12 on the hood lie in the pockets 15 in the L-shaped recess so that the wiring base must be forced upwardly before it can be rotated for releasing it from the hood.

The bayonet joint connection between the neck of the reflector and the hood may also be substantially as shown in my previous Patent No. 1,834,318 comprising a plurality of lugs 16 extending inwardly from the skirt of the hood and the sheet metal connector member 9 secured to the flange 17 of the reflector having a plurality of upwardly bent portions, three of which are provided with outwardly extending flange portions 18 for engagement with the inwardly extending lugs 16 on the hood. Each of these outwardly extending flanges, as shown in Fig. 4, is provided with a sloping portion 19 which enables the flange to ride easily over the corresponding lug 16 on the hood, exerting a cam action whereby the wiring base 2 may be easily forced inwardly against its spring 14 in making the connection. Each flange is also provided with an offset raised portion 20 so that when the reflector has been rotated to bring this raised portion above an inwardly extending lug 16 on the hood, the spring 14 will press the wiring base, and consequently the reflector member, downwardly. There is a slightly inclined shoulder portion 21 (Fig. 4) between the in-

clined cam portion 19 and the raised portion 20 of the flange, which inclined shoulder portion tends to resist disconnecting movement of the reflector. In my previous patent, this shoulder 5 was made abrupt so that it could not ride over the inwardly projecting lug in the disconnecting operation, thus necessitating forcibly pressing the reflector upwardly before rotating the reflector to disconnect it. As pointed out above, 10 however, this had disadvantages, particularly in the pendant type of fixture. In order to make the disconnection easy and still insure against accidental disconnection, I have provided the spring pressed plunger 10 which acts as a latch 15 when the reflector is in connected position by snapping off from the raised portion 20 of the flange onto one of the three shoulders 22 provided on an adjacent upwardly extending portion 23 of the connector member 9. This latch 20 will prevent any accidental rotation of the reflector member with respect to the hood. However, this latch member can be easily lifted against the slight tension of the latch spring 24 and thereafter the reflector can be disconnected 25 simply by giving it a slight rotation, the inclination of the shoulder portion 21 being so slight that the reflector can be rotated with respect to the hood without pressing upwardly on the reflector, the inclined shoulder acting as a cam to raise the reflector slightly.

As shown in Fig. 5, the upper surface of each of the lugs 16 may be rounded off for cooperation with the flange portions 18 so that these flange portions can ride over the lugs 16 easily, 30 even if abrupt shoulders are provided in the flanges as disclosed in my Patent No. 1,834,318 instead of the inclined shoulders 21 shown in this application.

As shown in Fig. 6, the wiring base is provided 35 with suitable wiring terminals 25 and 26, the wiring terminal 25 being electrically connected with the spring contact fingers 3, and the other wiring terminal 26 being electrically connected with the spring contact fingers 4.

In connecting the reflector with respect to the hood, the reflector is turned so that the flanges 18 will be out of alignment with the lugs 16 on the hood and the reflector is then pushed up to bring the entering edges of the flanges 40 above the inwardly extending lugs 16 on the hood. In this upward movement of the reflec-

tor, the plunger 10 is pushed upwardly by the engagement of one of the outwardly extending flange portions 18 with the head of the plunger. The reflector is then given a turning movement, the flange portions 18 riding along above the lugs on the hood, forcing the wiring base 2 inwardly by cam action. The reflector is turned until the little shoulders 21 on the flange are past the lugs 16, allowing the raised portions 20 of the flanges to rest on the lugs. When 10 turned to this position, one of the shoulder portions 22 is brought underneath the head of the plunger and the plunger snaps off from the laterally extending flange 20 onto the shoulder 22, thus holding the reflector against rotation. 15

Further modifications will be apparent to those skilled in the art and it is desired, therefore, that the invention be limited only by the prior art and the scope of the appended claim. 20

Having thus described my invention, what I 25 claim and desire to secure by Letters Patent is:

A lighting construction comprising a hood, a wiring base in and carried by said hood having contacts thereon, a reflector member, a lamp socket carried thereby having contacts for engaging the contacts on the wiring base, bayonet joint means whereby the reflector carrying the socket may be connected and disconnected with respect to the hood and wiring base by rotation about the axis of the reflector, spring means acting on the wiring base to hold its contacts in engagement with the contacts on the lamp socket, said bayonet joint connection having a cam engagement with the hood which in cooperation with the spring causes an in-and-out 35 movement of the wiring base both on the connecting and disconnecting movement, and spring latching means for positively holding the bayonet joint in connected position accessible for releasing operation from the exterior of the hood, 40 said hood having a guideway in its side wall extending longitudinally of the axis of the hood, said latching means comprising a plunger slidably mounted in said guideway, said plunger being provided with a lateral projection adjacent 45 the upper end of the hood whereby the plunger may be held in raised position by the hand gripping the hood and disconnecting the reflector from the hood.
